CUSHIONED BATH AID

Pansy E. Essman, 456 N. 8th St., San Jose, Calif.

Filed May 18, 1964, Ser. No. 80,015

Term of patent 14 years

(Cl. D4—4)

FIG. 1

FIG. 2

FIG. 4

FIG. 3

FIG. 5

FIG. 6

FIG. 1 is a plan view of a cushioned bath aid showing my design;

FIG. 2 is a side elevational view thereof;

FIG. 3 is a front elevational view thereof;

FIG. 4 is a rear elevational view thereof;

FIG. 5 is a bottom plan view thereof; and

FIG. 6 is a cross-sectional view on a reduced scale taken in the plane indicated by the line 6-6 in FIG. 1.

I claim:

The ornamental design for a cushioned bath aid, as shown.
